UNITED STATES PATENT OFFICE.

WILLIAM WILLS, OF PHILADELPHIA, PENNSYLVANIA, ASSIGNOR OF ONE-HALF TO
JOSEPH G. EVANS, OF PHILADELPHIA, PENNSYLVANIA.

INTERNAL-COMBUSTION ENGINE.

Application filed September 2, 1927. Serial No. 217,046.

My invention relates to motors and more especially to multiple cylinder internal combustion engines.

Among the objects of the invention are to 5 provide a motor of the above type in which the cylinders are arranged in a concentric circle or series and adapted to act upon a common power or drive shaft so that forces produced by a series of successive explosions 10 are caused to act upon a common power transmitting member to produce a maximum of power for a minimum sized motor.

Other objects of the invention are to provide a motor of the above type which is compact; which relieves the chassis of vertical thrusts and vibrations; to provide a novel arrangement of intake and exhaust manifolds for the various cylinders; to improve the valve construction and operating means 20 therefor; to provide an improved lubricating system for the various working parts, and to generally improve and increase the efficiency of motors of the type to which the invention relates.

25 The construction by which the above objects are accomplished comprises a plurality of cylinders having pistons working therein, said cylinders being annularly arranged within a block having a central bore, the cylinders being provided with the usual intake and exhaust valve construction connecting the cylinders respectively, with the intake and exhaust manifolds, the former being arranged within the bore and the latter circumferentially of the block.

30 The pistons are connected with a wabbler which is mounted by a ball and socket universal joint so that the wabbler may assume various positions under the influence of the pistons. The wabbler is flexibly connected by suitable means to the fly-wheel of a driving shaft.

35 Suitable mechanism is also provided for opening and closing the intake and exhaust valves of the various cylinders in timed relation to each other.

In the drawings:—

Figure 1 is a front elevation of the improved motor,

50 Figure 2 is a vertical sectional elevation taken on the line 2—2 of Figure 1,

Figure 3 is an enlarged vertical cross section taken on the line 3—3 of Figure 2,

Figure 4 is an enlarged fragmentary sectional view corresponding to Figure 2 but showing only one cylinder,

Figure 5 is a vertical cross sectional view taken on the line 5—5 of Figure 2,

Figure 6 is an enlarged fragmentary detail sectional elevation of a power transmitting plate and its mounting, together with a piston to illustrate the connection of the pistons with the plate and the manner of lubricating the associated parts,

Figure 7 is a sectional view taken on the line 7—7 of Figure 6,

Figure 8 is a perspective view of the power transmitting plate and adjacent parts,

Figure 9 is an enlarged sectional view taken on the line 9—9 of Figure 8,

Figure 10 is an edge view of a universal cross pin employed in the mounting of the power transmitting plate,

Figure 11 is a face view of Figure 10, and

Figure 12 is a sectional view in the plane of the axes of the pins.

Referring to the drawings in detail, my improved engine or motor comprises a cylinder block 10 having a series of concentrically arranged cylinders 11 spaced equidistantly from each other and the common center, the combustion chambers of which are provided with water jackets 12. An odd number of cylinders is employed, with pistons 13 working therein, so that each alternate piston will be successively operated in connection with the timing and ignition system employed in a four-cycle motor. The rear ends of the cylinders are open and the cylinder block is provided with a central axial bore 14 and inner and outer circumscribing flanges 15 and 16 positioned at right angles to the axis.

A cylinder head 17 is bolted to the body portions of each cylinder, as indicated at 18, and forms end walls 19 of the combustion chamber and water jackets 20 communicating with the water jackets 12 through the openings 21 so that a circulation of water is maintained over end walls 19 as well as around the lateral walls of the cylinders.

The inner portion of the cylinder head 17 is provided with an intake manifold 22, which

communicates, through an intake pipe 23 leading radially through the inner wall, with a fuel supply device or carburetor 24 in the central bore 14 in the rear of the water jackets 5 12 and receives its fuel supply through a pipe 25 in the customary way.

Leading from the manifold 22 are intake passages 26, having intake ports provided with inclined seats 27 facing downwardly 10 and rearwardly. Co-acting with these seats are inwardly opening intake valves 28 having valve stems 29 operating in inclined guides 30 from which the stems project to receive expandable springs 31 which normally hold the 15 valves seated and the ports from the intake manifold to the cylinders closed.

The exhaust manifold is indicated at 32 and communicates with the cylinders through head passages 33 having ports provided with 20 seats corresponding to the seats 27 and valves 34 corresponding to valves 28, except that valves 28 control the supply of combustible mixture to the cylinders while valves 34 control the exhaust of spent gases and products 25 of combustion. Should the stems of the valves 28 or 34 break or be otherwise disconnected and the heads drop into the cylinders 11, the heads will be supported clear of the pistons, as shown in Figure 4 of the drawings, 30 thus preventing injury or jamming of the parts, or scoring of the cylinders. All of the valves are alike in structure and their stems are engaged by arms 35 pivoted on brackets 35 fixed to cylinder head 17 as indicated at 36.

The arms 35 are provided with threaded sleeves 37 in which the valve rods 38 are adjustable, said valve rods comprising sections connected by ball and socket joints 39 to allow for angular movement of the arms. 40 The rods 38 extend through rod guides 40 in the bottom of a housing 41 supported above and slightly in front of the cylinder head 17 as by means of brackets 42. Engaging the upper ends of these valve rods are valve lifters 45 43 operating in blocks 44 mounted across the housing, as indicated at 45, and having their inner ends spaced apart as shown. The lower ends of these valve lifters are provided with oil shed skirts 46 so that oil will drain into 50 the bottom of housing 41 and down oil grooves 47 into drain pipes 48 and thence through pipe 49 to an oil pump 50 mounted in a case 51 attached to flanges 15 and 16.

Journalized across the housing above the blocks 44 in bearings 52 and 53, is a cam shaft 54 having cams 55 engaging the upper ends of valve lifters 43 in such relation as to time the opening and closing of the intake and exhaust valves of the cylinders, so that each 60 alternate piston will be successively operated during the running of the motor. The cam shaft 54 is driven by a worm 56 from a horizontal shaft 57 rotatably supported above the motor casing, the space between the blocks 44 accommodating the intermeshing worm

and worm gear as shown in Figure 3 of the drawings. The shaft 57 is journaled in a sleeve 58 supported above the motor casing by brackets 42 and 59 and 60 and carries the usual cooling fan 61 at its front end. The 70 housing 41 is provided with a removable cover 62 by which access may be had to the internal mechanism.

Internal webs 64 are formed in each piston 13 and provided with a socket 65 in which is 75 positioned a cup bearing 66 for receiving the ball 67 formed on the end of a connecting rod 63. The sockets are internally threaded to receive sleeve nuts 68 in which the connecting rods are held from displacement but 80 have slight play. The other ends of connecting rods 63 are provided with ball terminals 69 engaged in sockets 70 carried by a power transmission plate or wabbler 71. This wabbler is provided with internally threaded 85 sleeve portions receiving plugs 72 having concaved ends conforming to the ball terminals 69 which are retained in position for angular movements by sleeve nuts 73, thus providing separable ball and socket joints in the form 90 of plugs which in conjunction with the ball and socket joints of the pistons, permit adjustment of the strokes of the pistons so that they will be uniform, convenient of assemblage, of disassembly and will provide for 95 compensation for wear of the parts.

The wabbler 71 is mounted centrally to oscillate so that the radii of the wabbler will move in a constantly changing angle as the pistons reciprocate. For this purpose, the case 51 has a plate 74 attached to flanges 15 and 16 of cylinder block 10 and covering the bore 14 between the cylinders 11. To the central portion of plate 74, a rearwardly extending bearing bracket 75 is bolted. This bracket is provided with upper and lower arms 76 forming a forked extremity in which the ends of a vertical pin 77 have pivotal bearing. The vertical pin 77 is formed integral with a horizontal pin 78, thus forming a cross-pin 79, the ends of the pin 78 being pivoted in bearings 80 attached to the front of wabbler 71 in horizontal alignment upon opposite sides of a hollow boss 81, which receives the cross-pin and arms of the bracket. The back of the wabbler at the boss 81 is provided with a clamp 82 in which an arm 83, extending axially of the plate, is fixed and extends rearwardly and is pivotally connected, as indicated at 84, with a fly wheel 85 secured to a shaft 86, which has bearings in case 51. Shaft 86 is operatively connected, through the medium of a clutch 87 operated by a controlling member 88 and transmission gearing 89 operated by lever 90, to drive the vehicle. The pump 50 is geared to shaft 86 as indicated at 91 while shaft 57 may be driven at the required speed in any desired manner as through the medium of an endless drive member 92 trained over pulleys or 105 110 115 120 125 130

sprocket wheels 93 and 94 on the shafts 57 and 86.

The oil pump 50 supplies lubrication to the cam shaft and valve lifters in the housing 41 through pipes 95 having ports or openings 96 above each cam. One end of each pipe 95 is disposed adjacent to and above a bearing 53 for lubricating it and the worm and worm gear. The other end of each pipe 95 is connected into a bearing 52 where it intermittently communicates with a transverse passage 97 in shaft 54 which connects with an axial passage 98 communicating with an oil pipe 99 leading from oil pump 50 and disposed at the sides of housing 41.

An oil supply pipe or tube 100 leads upwardly along and through a passage 101 in one arm of bracket 75 then through a peripheral groove and diametrical passage 102 in one end of pin 78 to axial passages 103 and 104 in pins 77 and 78, to oil the bearings for the pins. The oil then passes out through tubes 105, branching from the ends of pin 78, to the ball and socket joints 70, where rods 63 connect to wabbler 71, through diametrical passages 106 in the ball terminals. The oil then flows through axial ducts or passages 107, in the connecting rods through diametrical passages 108 to the ball and socket connections of the rods with the pistons 13, from which the oil under pressure escapes and drops into the case 51.

In the operation of the engine, the intake valves 28 will be opened by depression of stems 29 by engagement of cams 55 with valve lifters 43 and consequent depression of valve rods 38. The gaseous mixture from the carburetor 24 will then be supplied to the cylinders through the intake pipe 23 and manifold 22 in properly timed relation. As the pistons 13 move forwardly, the gas will be compressed in the respective cylinders 11 and exploded by suitable ignition operating harmoniously with the timing mechanism. Each alternate piston will be successively forced outward on the working stroke, thus causing wabbler 71 to oscillate on its universal mounting at the center. The spent gases will then be exhausted, by the opening of the exhaust valves 34 valve operating mechanism, and escape through the exhaust manifold 32. The valve operating mechanism is driven from shaft 57 which also rotates fan 61. The oscillation of wabbler 71, as the pistons are reciprocated, imparts a circular motion to the axial arm 83 which has rotatable connection with fly wheel 85, thus driving the fly wheel and shaft 86 through which power is transmitted. The oil pump 50 and shaft 57 are driven from shaft 86 and during the operation of the motor, a thorough circulation of lubricating oil is provided for.

Details of the mechanism hereinbefore described may be changed and modified within

the scope of the invention hereinbefore set forth and hereinafter claimed.

I claim:

1. An internal combustion engine including a plurality of horizontal cylinders disposed equidistant from a common center, valves in the cylinders, valve operating mechanism disposed above the cylinders and operatively connected to the valves, pistons in the cylinders, a drive shaft having a flywheel thereon, and a wabbler operatively connected to the pistons and to the flywheel.

2. An internal combustion engine including a horizontally disposed cylinder block having a plurality of cylinders equidistant from a common center, a cylinder head closing one end of all of said cylinders, valves in the cylinder head, mechanism for operating the valves mounted on and above the cylinder head, pistons in the cylinders, a wabbler mounted on the common center, connecting rods connected between the pistons and wabbler, a drive shaft having a flywheel thereon, an arm extending from the wabbler and rotatably connected to the flywheel eccentrically thereof, a shaft rotatably mounted above the cylinder block for actuating the valve operating mechanism, and means mechanically connecting said shaft with the drive shaft.

3. In an internal combustion engine of the character described having a stationary cylinder block containing a central bore and a plurality of cylinders equally spaced around the bore; a cylinder head having an exhaust manifold concentric with and outwardly of the cylinders, an intake manifold concentric with and inwardly of the cylinders and ports connecting each cylinder to each manifold; a fuel regulator disposed in the central bore and communicating with the intake manifold; and valves closing the ports.

4. In an engine of the character described having a vertically disposed cylinder head containing a plurality of angularly disposed spring pressed valves, means for opening the valves including a cam shaft rotatable above the cylinder head, valve lifters operable by the cam shaft, hinged arms engaging the stems of the valves, and valve rods connecting the arms and valve lifters.

5. In an engine of the character described having a vertically disposed cylinder head containing a plurality of angularly disposed spring pressed valves, means for opening the valves including a cam shaft rotatable above the cylinder head, valve lifters operable by the cam shaft, hinged arms engaging the stems of the valves, valve rods connecting the arms and valve lifters, and a universal joint formed in each valve rod intermediate its ends.

6. An engine of the character described including a cylinder block having a central bore; a plurality of cylinders concentric there-

with ; pistons in the cylinders ; a cylinder head secured to the body of each cylinder forming the end wall of the combustion chamber and enclosing an intake manifold communicating with an intake pipe leading through the central bore of the cylinder block ; an exhaust manifold disposed outside the series of cyl-

inders, each manifold having ports communicating with each cylinder ; valves normally closing the ports, and means for intermittently opening the ports. 10

In testimony whereof I have signed my name to this specification.

WILLIAM WILLS.
